COMBINED SOAP DISH, GRAB BAR, AND COLLAPSIBLE SHELF FOR SHOWER STALLS

George J. Lind, Balboa, Calif.

Application August 13, 1951, Serial No. 16,249

Term of patent 14 years

(Cl. D4—3)

To all whom it may concern:

Be it known that I, George J. Lind, a citizen of the United States, residing at Balboa, in the county of Orange, State of California, have invented a new, original, and ornamental Design for a Combined Soap Dish, Grab Bar, and Collapsible Shelf for Shower Stalls, of which the following is a specification, reference being had to the accompanying drawing, forming a part hereof.

Fig. 1 is a perspective view of a combined soap dish, grab bar, and collapsible shelf for shower stalls embodying my new design, the shelf being shown in collapsed or closed position;

Fig. 2 is a view similar to Fig. 1 but illustrating the shelf in open or extended position; and

Fig. 3 is a horizontal section taken substantially upon the line 3—3 upon Fig. 1 in the direction indicated.

I claim:

The ornamental design for a combined soap dish, grab bar, and collapsible shelf for shower stalls, as shown.

GEO. J. LIND.
